UNITED STATES PATENT OFFICE.

JAMES F. DUFFY, OF CHICAGO, ILLINOIS.

MANUFACTURE OF BLACKSMITHS' SWAGES.

SPECIFICATION forming part of Letters Patent No. 259,113, dated June 6, 1882.

Application filed December 31, 1881. (No model.)

To all whom it may concern:

Be it known that I, JAMES F. DUFFY, of Chicago, in the county of Cook and State of Illinois, have invented certain new and useful

5 Improvements in the Manufacture of Blacksmiths' Swages; and I do hereby declare that the following is a full, clear, and exact description of the invention, which will enable others skilled in the art to which it appertains to 10 make and use the same, reference being had to the accompanying drawings, and to letters of reference marked thereon, which form a part of this specification.

Heretofore it has been the custom to make 15 blacksmiths' swages by hand, by which method even the exercise of the greatest care is incapable of producing a uniformly good tool, for a defective blow of the striker on the top tool or an unsteady hand of the blacksmith when 20 holding the "fuller" is likely to throw the tool being made out of balance—that is, make it out of proportion and destroy its symmetry of form, or make the groove in the operating-face of the said tool run obliquely instead of centrally and longitudinally, as it should be. My 25 method overcomes these difficulties by making swages in one heat with dies inserted in the ram of a power-press or hammer of a drop-hammer. Its object is, first, to make a swage 30 or any given number of swages perfect and uniform in construction, having the semicircular groove running longitudinally and central, and having the proportion or balance of metal in all parts equal and perfect; second, to save labor, the estimated saving of which is as one to 35 twelve, (1 to 12;) third, to save material, no waste being necessary and little, if any, oxidation happening; and, fourth, to preserve the quality of the steel by completing the swage 40 in one heat instead of a number of heats, as heretofore, which materially deteriorates the quality of said steel.

Similar letters of reference represent like parts in the several figures of the drawings, in 45 which—

Figure 1 shows the construction and arrangements of the dies in the head-block. Fig. 2 is a perspective view of a blacksmith's swage, and Fig. 3 is a plan view of the same.

50 In the drawings, A represents a swage of the usual construction in current use among black-

smiths. It is provided with a tang, a, which is inserted in an anvil, and in its operating-face is a groove, a', semicircular in cross-section, which should run longitudinally in the 55 center of width of the swage. This, however, is seldom the case, for when made by hand—and applicant knows of no other method heretofore employed—it is almost impossible to make an absolutely perfect swage. The swage commonly made is somewhat distorted in the shape, as shown in dotted lines in Fig. 3, the groove either being oblique or more metal being on one side of the groove than on the other, throwing the swage, practically speaking, out of balance.

To make swages by my method I place side by side a die, B, for forming the operating-face of the swage and a plane-faced die, C, for drawing out the tang. Both of these dies have 70 tangs b and c, which enter corresponding sockets or holes in the head-block D, being secured therein by set-screws or keys b' and c'. The head-block D is provided with a cylindrical tang, d, by means of which it is secured in the 75 ram of a power-press or hammer of a steam or drop hammer. In making the swages the tang is first drawn out by the plane-faced die C, after which the face of the swage is formed by the die B, said die consisting of a depression 80 having beveled walls and an operating-face provided with a ridge semicircular in cross-section and running centrally and longitudinally over said face. In order that the under side of the swage may have a solid bearing when used in 85 an anvil, and that the tang of said swage may not be injured when the operating-face of the same is being made, I make a hole or depression, e, in the anvil or base E, corresponding in dimensions to the tang of the swage. Thus 90 the same blow which forms the operating-face of the swage contributes to make the under side of the head of said swage perfectly plane, so as to bear flat on the face of the anvil.

What has been said concerning the manufacture of the bottom tool is equally applicable to the upper tool, the manufacture of both being considered within the scope of my invention.

The above-described method enables me to 100 do in one heat what has heretofore required a dozen heats, thus not only saving the metal

from scaling or oxidation, but preserving the quality of the steel.

What I claim as new, and desire to secure by Letters Patent, is—

5 A die for forming blacksmiths' swages, having a depression in its face consisting of side beveled walls, a plane operating-face, and a ridge semicircular in cross-section running centrally and longitudinally over said operating-

10 face, in combination with an anvil or base having a hole or depression corresponding to the

tang of a swage, and located immediately under the center of said die, substantially as and for the purpose hereinbefore described and set forth.

15 In testimony that I claim the foregoing as my own I hereby affix my signature in presence of two witnesses.

JAMES F. DUFFY.
